FORD S. MILLER, OF NEW SALEM, KANSAS

CLUTCH MECHANISM

Application filed July 10, 1929. Serial No. 377,195.

This invention relates to clutch mechanisms and has as its primary object the provision of an improved mechanism of the class mentioned which will obviate the necessity of the use of ring gears.

Another very important object of this invention is to provide a mechanism of the above mentioned character, in which is developed improved means for operatively connecting the motor shaft to the drive shaft of a differential for imparting alternate rotation in opposite directions to the drive shaft, and for imparting forward or rearward motion to the vehicle with which my mechanism may be incorporated.

Other objects and advantages of the invention will become apparent from a study of the following description taken in connection with the accompanying drawings, where-

20 in:

Figure 1 is a view partly in section, and partly in elevation through a clutch mechanism constructed in accordance with this invention illustrating a forward and reverse clutch for automobiles or any suitable motor.

Figure 2 is an end view partly in section and partly in elevation looking into the casing from the left hand side of Figure 1.

Figure 3 is a view similar to Figure 1, showing a modification of the invention, and illustrating how both forward and reverse motion can be controlled through the medium of a single control.

Figure 4 is a view similar to Figure 2, the end of the outer casing being removed.

Figure 5 is a vertical transverse sectional view, taken substantially on the line 5—5 of Figure 3, and looking in the direction of the arrow.

With reference more in detail to the drawings, and wherein like numerals designate similar parts throughout the several views, it will be seen that 5 is the main drive shaft or motor shaft which extends into and is journaled in a bearing 7 formed in the cover 6 of a casing A, as clearly shown in Figure 1, and the said shaft 5 extends horizontally within the casing and on its inner end is provided with a double bevelled gear 8. As shown, the gear 8 is of peculiar construction having

oppositely bevelled edges so as to provide as it were a double faced bevelled gear.

Arranged within the casing A and rotatably mounted on the drive shaft 5 and driven shaft 5' is a housing B. The housing B is so formed as to provide a gear compartment C and a pair of laterally extending spaced compartments D. These compartments D constitute cylinders and are to be filled with oil, air, or like fluid, for a purpose to be herein-after more fully set forth. The inner walls of the compartment B constitute a suitable bearing for the reception of the main motor shaft 5, as illustrated. It is also to be noted that at their inner ends the compartments D communicate with the gear chamber C. The compartments D are of course closed at their outer ends and through which closed ends extend suitable valve casings 9—9. The purpose of these valve casings will be hereinafter more fully set forth. Journalled within the gear compartment C of the housing B is a gear shaft 11, said gear shaft having reduced extremities at its opposite ends, the reduced extremities being journaled in opposite walls of the housing B. Keyed to the reduced extremities of this shaft 11 are the bevelled gears 12—12.

The differential drive shaft 5', which is journaled in the rear wall of the casing A so also extends into the housing B, and has on its inner end and located within the chamber C of the said housing, the bevelled gear 13. Thus it will be seen that the gear 8 and gear 13 are in opposed relation, on diametrically opposite sides of the shaft 11.

In this connection it will be seen that as the motor of the vehicle is running, the housing B and the shafts 5 and 5' will all rotate in the same direction. Consequently, if the housing B were stationary, and the motor running, the shaft 5' will rotate in the opposite direction. If friction be applied between the gears 12—12 and the housing B, or the gears 12—12 be stationary, the differential shaft 5' would move in the direction of the motor. Consequently, if friction were applied to the housing B, a pressure would be exerted on the differential drive shaft 5', causing it to move through the medium of the

gearings 8, 12—12 and 13 in a direction of rotation opposite from the shaft 5, as is apparent. This of course would be very well for a reverse. However, it would be a waste of power, and cause noise and wear on the moving parts of the clutch to have anything turning when the vehicle was in a forward motion. Thus, by having the gears 14 and 15 respectively, said last named gears being arranged on crank shafts 16 and 17 respectively, journaled respectively in each of the cylinders D—D, adjacent the open ends of the cylinder in operative relation to the double bevelled gear 8, for mesh with said gear 8, friction may be applied very gradually between the gear 8 on the motor shaft and the housing B as will be fully appreciated, when the following operation and construction is considered.

In this connection, then, it will be seen that I provide on each of the crank shafts 16 and 17, a pair of alternately operating reciprocating pistons, said pistons being arranged in pairs, the pistons of the respective pairs being operatively associated with the crank shaft on opposite sides of each of the gears 15 and 14 respectively. As shown, adjacent their closed ends, each of the cylinders D—D are provided with intermediate walls D'. These walls provide chambers for the pistons of the respective pairs operable within the cylinders. Obviously the pistons of the respective pairs have their connecting rods fixed as designated generally as at 19, to the crank of the respective crank shafts 16 and 17 formed thereon at opposite sides of the gears 14 and 15. Of course it is to be understood that the gears 14 and 15 are each bevelled gears for suitable mesh with the gear 8.

The closing or outer walls of the cylinders D are each provided with intake ports 20 and 21, formed therein and communicating with the outlet port of the valve casing 9 and the piston chamber of the respective cylinders D—D.

Slidable on the motor shaft 5 is a disc 22, said disc being provided with a hub 22', which is externally and circumferentially grooved as illustrated. This disc is disposed on the shaft in operative relation to the outer ends of the respective valve casings 9. Adapted for reciprocatory movement within each of the valve casings are the double valves 9'. The doubled valves are connected through the medium of a single or common valve stem, one end of which valve stem extends into a suitable bore, formed on the outer face of the bisecting walls D' of the cylinders and are normally held in a closed position through the medium of springs 23 located within the bores, one end of the spring extending against the said inner end of the valve stem, for urging the pins outwardly of the valve casing as is apparent. When the valves 9'

are closed, there is produced a lock unit, forward drive, as is apparent.

Manually controlled means are utilized for imparting a sliding movement to the disc 22 upon the shaft 5, for controlling the opening and closing of the valves. This means includes a horizontally disposed transversely extending shaft 24, arranged adjacent the forward end of the casing A, said shaft having its opposite ends journaled in suitable bearings 25, at opposite diametrical points on the casing. The shaft 24 is of course adapted for rocking motion and has fixed thereto intermediate its ends, in any suitable manner the shank 26 of a forked member 27. The legs of this forked member 27 extend on opposite sides of the hub of the disc 22, the extremities of the legs being provided with inwardly directed extensions 27', located within the groove of the hub 22'. Rocking movement of the shaft 24 being imparted thereto from the operator of the vehicle through the medium of an operating lever 28, which extends upwardly through the forward part of the vehicle in convenient reach of the operator of the vehicle. This operating lever 28 is secured at its lower end to one end of the shaft 24, which extends exteriorly of the casing A as shown to advantage in Figure 2. The said lever 28, being moved in one direction, will of course force the disc 22 into engagement with the stem of the valve, moving the valve to an open position, to permit movement of the pistons. When valves 9' are closed a reduction in the speed of rotation of the shaft 5 and gear 8 will result, since said shaft and gear will then be acting against a pressure caused through the actuation of the pistons against fluid in the cylinders D through the gears 14 and 15. Of course, during this time, it is to be assumed that the differential shaft 5' is being driven through the medium of the intermeshing gears.

The housing B has a split ring 28, circumjacent that portion of the housing B, which constitutes the gear chamber C. This split ring or band 28 is provided on its inner face with a suitable wear band 29, the construction being such as to simulate the construction of friction brakes. The ears on the band 28 are of course provided with aligned internally threaded apertures for threaded engagement with a suitable screw 30 rotatable in a housing 31, on the top of the casing A as shown in Figure 2. To one end of the screw 30 there is secured, as at 32, an operating lever 33, said lever also extending upwardly through a forward portion of the vehicle to be in convenient reach of the operator of the vehicle. Thus it will be seen that upon operation of the lever 33, the ends of the bands 28 will be drawn toward one another through the operation of the screw 30, it being understood, of course, that the

5 screw 30 is provided with suitable right and left hand threads as clearly illustrated. This drawing of the ends of the bands together will consequently frictionally engage and tighten the band about the housing B, placing a load upon the housing B, which will, of course, cause the shaft 5 to move in a direction of rotation opposite from the shaft 5.

10 For the purpose of convenience, the band 28 may be termed the reverse band.

From the foregoing then, it will be seen that in neutral position the valves 9' controlling the pistons are opened, and the reverse band 28 is released. By pulling back upon the operating lever 33, the reverse band 28 will be tightened about the casing B, and the lever 28 is actuated for moving the valves 9' to an open position, so that, the gear 8 15 rotatable on the driven shaft 5 through the medium of the gears 12 will rotate the driven shaft 5' in an opposite direction, the pistons at this time working back and forth, and the vehicle is standing in reverse motion. To 20 go forward, the operator actuates the lever 33 for releasing the reverse band 28 and further actuates the lever 28 for gradually closing the valves 9' thus gradually slowing down the movement of the pistons and when 25 these valves are closed there is produced a lock unit, forward drive.

Manifestly, when the valves are closed, the pistons will not move and then each shaft 5 and 5' will have the same speed. In this 30 connection then, it will be noted that this tightening of the band about the housing B will act as a brake when the car is in forward motion, while the operation of the pistons will act as a brake when the car is in reverse.

40 In the modified form of my invention as illustrated in Figures 3 to 5 inclusive, the operation is substantially the same and as there-in illustrated the said modification embodies the outer casing A' through which extends in opposed relation the motor shaft 5^a, and the differential shaft 5^b. There is also provided within the outer casing A', the housing B' embodying the piston chamber or cylinder D'', the said housing B' adapted to be engaged with the said shafts, in the same manner as described with reference to the housing B. The motor shaft and differential shaft are each provided with their opposed 45 gears 8' and 13', located within the gear chamber C' of the housing B'.

50 However, in this embodiment of the invention, the gears 12', 12' which correspond to the gears 12—12 are each journaled on a crank shaft 39, 39. The crank shafts 39—39 each have one end thereof suitably journaled in the walls of housing B', the opposite ends of the shaft being journaled in a suitable bearing member 14', which extends horizontally and transversely within the chamber

5 C', said member being surrounded by the gears 8', 12', and 13'. The gears 12' are fixed to and are adapted for rotation with the crank shafts 39, 39. Adapted for alternate reciprocatory movement within the cylinders D''—D'' are the pistons 40 and 41 respectively, there being but one piston in each of the said cylinders. These pistons have their connecting rods 40' and 41' respectively connected to the cranks of each of the crank shafts 39. The cylinders D''—D'' are each provided with lateral intake openings 42, and these openings are each controlled by suitable valves 43. As shown the valves 43 are spring pressed, being operable through the closing or end wall of the respective cylinders, adapted for reciprocatory movement within suitable bores formed on the side walls of each of the cylinders, the lower end of the valves extending into the bores, coil springs 44 arranged within said bores, impinging against the said end of the valve for normally urging the valve outwardly for positioning the ports 43', of said valves to open position within the port 42 of the cylinders (see Figure 3).

55 The valves 43 similar to the valves 9' are to be actuated through the medium of a disc 22^a, on the motor shaft 5^a, said disc being also slidably received thereon and provided with the externally grooved hub 22^b. For operating the disc for controlling the valve, there is provided a suitable rock shaft 24' having its opposite ends journaled in diametrically opposed bearings formed on the outer casing A' (see Figure 4). Depending from the shaft 24' is the member 26', said member having a shank at its upper end fixed to an intermediate portion of the rock shaft 24' and said shank at its opposite end terminating in a fork, the legs of which are disposed along diametrically opposite sides of the hub 27^b and engageable in the groove of the hub as shown. Circumjacent the housing B' in the same manner with regard to the housing B, is a split ring or band 28', which is formed at its opposite end with suitably internally threaded apertured ears for the threaded reception of the screw 30' and in this connection, it is to be seen that the screw 30', unlike the screw 30 is provided with spiral threads, the threads extending in but one direction, there being formed thereon no right and left hand threads as in the case of the first mentioned screw. This screw is also operable within a suitable housing 31' formed on the outer casing A'.

60 The band 28 is also provided with the lining 29', all of which is engageable with the housing B' in the manner as described with regard to the preferred form of my invention. In this form of my invention, I prefer a simultaneous operation of the valves 43 and the friction band 28'. Accordingly, the rock shaft 24' on that end of which extends ex-

teriorly of the casing A' is provided with a link 45, said link 45 being in the nature of a crank arm, the opposite end of the crank arm 45 being pivotally connected as at 46 to the operating lever 33', which extends upwardly from one end of the screw 30' to project into the forward portion of the vehicle within convenient reach of the operator of the vehicle as is the case with the operating lever 33, the link 45 being operatively connected with said rock shaft 24', by a crank as at 47. Thus it will be seen that by the actuation of the lever 33', the disc 22^a will be actuated on the shaft 5^a for controlling the valves 43 and the band 28' simultaneously actuated therewith for frictional engagement with the housing B'. This of course, without materially differing the operation of the mechanism, with regard to the operation as disclosed in the preferred embodiment of my invention. The only difference of course being the provision of the pistons operatively associated with the gears 12', consequently acting as a braking action for the shaft 5^a.

25 From the foregoing then, it will be seen that I have provided an improved clutch mechanism, which is comparatively simple in construction, strong, durable, practical, thoroughly reliable and positive in operation, and otherwise well adapted for the purpose intended. It is believed that from a study of the following description, taken in connection with the accompanying drawings, a thorough knowledge of the operation, construction, and advantages of a clutch mechanism constructed in accordance with this invention will be fully gleaned and readily understood by those skilled in this art. A more lengthy description thereof is deemed unnecessary.

40 Even though I have shown and described the preferred embodiment of my invention, it is to be understood that the same is susceptible to changes fully comprehended by the spirit of the invention as herein described and the scope of the appended claims.

What is claimed is:

1. In a clutch mechanism of the class described, a drive shaft, a driven shaft, a housing rotatably mounted on said shafts, each of said shafts having a gear mounted on the inner end thereof, said gears being disposed in opposed relation, a pair of oppositely disposed gears rotatably mounted in said housing intermediate the first mentioned gears and adapted for mesh therewith, said housing having a plurality of cylinders formed therein, pistons mounted for reciprocation within said cylinders, and means operatively connecting said pistons with the gear on said drive shaft.

2. In a clutch mechanism of the class described, a drive shaft, a driven shaft, a housing rotatably mounted on said shafts, each of said shafts having a gear mounted on the

inner end thereof, said gears being disposed in opposed relation, a pair of oppositely disposed gears rotatably mounted in said housing intermediate the first mentioned gears and adapted for mesh therewith, said housing having a plurality of cylinders formed therein, pistons mounted for reciprocation within said cylinders, and means operatively connecting said pistons with the gear on said drive shaft, a friction band disposed about said housing, and manually operable means for drawing said band into frictional engagement with said housing.

3. In a clutch mechanism of the class described, a drive shaft, a driven shaft, a housing rotatably mounted on said drive and said driven shafts, gears on the inner ends of said shafts within said housing, said gears being disposed in opposed relation, a pair of oppositely disposed gears rotatably mounted within said housing and adapted to mesh with the first mentioned gears, said housing having a plurality of cylinders formed therein, pistons mounted for reciprocatory movement within said cylinders, gears rotatably mounted adjacent one end of said cylinders, an operating connection between said pistons and the last mentioned gears, the gear on said drive shaft having teeth on opposite faces thereof, the teeth on one face thereof in mesh with the first mentioned gears in said housing, and the teeth on the other face of said gear adapted to mesh with the second mentioned gears, said cylinders being adapted to contain fluid, said cylinders having openings formed in the walls thereof, valves controlling said openings, manually controlled means for opening and closing said valves, a reverse band surrounding said housing and adapted for frictional engagement with said housing, said shafts and said housing adapted to rotate in the same direction when said valves are in an open position and said reverse band is out of engagement with said housing.

4. In a clutch mechanism of the class described, a drive shaft, a driven shaft, a housing rotatably mounted on said drive and said driven shafts, gears on the inner ends of said shafts within said housing, said gears being disposed in opposed relation, a pair of oppositely disposed gears rotatably mounted within said housing and adapted to mesh with the first mentioned gears, said housing having a plurality of cylinders formed therein, pistons mounted for reciprocatory movement within said cylinders, gears rotatably mounted adjacent one end of said cylinders, an operating connection between said pistons, the gear on said drive shaft having teeth on opposite faces thereof, the teeth on one face thereof in mesh with the first mentioned gears in said housing, and the teeth on the other face of said gear adapted to mesh with the second mentioned gears, said cylinders

being adapted to contain fluid, said cylinders having openings formed in the walls thereof, valves controlling said openings, manually controlled means for opening and closing said valves, a reverse band surrounding said housing and adapted for frictional engagement with said housing, said shafts and said housing adapted to rotate in the same direction when said valves are in an open position and said reverse band is out of engagement with said housing, and manually controlled means for moving said band out of frictional engagement with said housing whereby when said valves are moved to a closed position said drive and said driven shafts will be operatively connected to provide a forward drive.

5. In a clutch mechanism of the class described a drive shaft, a driven shaft, a housing rotatably mounted on said drive and said driven shafts, oppositely disposed gears carried by the adjacent ends of said shafts, intermediate gears carried by said housing and adapted to mesh with the first mentioned gears, said housing having a plurality of cylinders formed therein, said cylinders adapted to contain fluid, pistons mounted for reciprocatory movement within said cylinders, gears rotatable adjacent one end of said cylinders, an operating connection between said gears and said cylinders, the gear on said drive shaft having teeth on the forward and rear face thereof, the second mentioned gears adapted to mesh with the teeth on the rear face of said gear, the gear on said drive shaft having the teeth on its forward face adapted to mesh with the second mentioned gears in said housing, valve controlled openings in the walls of said cylinders, spring means normally maintaining said valves in a closed position, manually controlled means for moving said valves to an open position, a reverse band surrounding said housing, and means for simultaneously moving said valves to a closed position and for releasing the band about said housing.

6. In a clutch mechanism of the class described a drive shaft, a driven shaft, a housing rotatably mounted on said drive and said driven shafts, oppositely disposed gears carried by the adjacent ends of said shafts, intermediate gears carried by said housing and adapted to mesh with the first mentioned gears, said housing having a plurality of cylinders formed therein, said cylinders adapted to contain fluid, pistons mounted for reciprocatory movement within said cylinders, gears rotatable adjacent one end of said cylinders, an operating connection between said gears and said pistons, the gear on said drive shaft having teeth on the forward and rear face thereof, the second mentioned gears adapted to mesh with the teeth of the rear face of said gear, the gear on said drive shaft having the teeth on its forward face

adapted to mesh with the gears in said housing, valve controlled openings in the walls of said cylinders, spring means normally maintaining said valves in a closed position, manually controlled means for moving said valves to an open position, a reverse band surrounding said housing, and means for simultaneously moving said valves to a closed position and for releasing the band about said housing, said means also including means for maintaining said valves in an open position and for frictionally engaging said reverse band with said housing, whereby said shaft will be rotated in an opposite direction.

In testimony whereof I affix my signature.

FORD S. MILLER.
